GUSTAF DALÉN, OF LIDINGÖN, STOCKHOLM, SWEDEN.

APPARATUS FOR AUTOMATICALLY EXCHANGING INCANDESCENT BODIES.

1,210,769.

Specification of Letters Patent.

Patented Jan. 2, 1917.

Application filed July 17, 1914. Serial No. 851,671.

To all whom it may concern:

Be it known that I, GUSTAF DALÉN, engineer, residing at Skärsätra, Lidingön, Stockholm, Sweden, have invented certain new and useful Improvements in Apparatus for Automatically Exchanging Incandescent Bodies, of which the following is a specification.

My present invention relates to an apparatus for automatically exchanging incandescent bodies without interrupting the lighting to any considerable degree.

The accompanying drawings show, as examples illustrating the invention, some constructional forms of embodiment of the same in which the exchange of the said bodies is effected automatically by the action of a flame on a releasing device, such flame becoming effective when such incandescent body had been burst, ruptured, or broken.

It will be understood that changes in the details of construction may be made within the scope of the claims without departing from my invention.

In order that my invention may be readily understood and comprehended reference should be had to the accompanying drawings in which,—

Figure 1 is a view partly in vertical section and partly in side elevation of an apparatus embodying my invention; Fig. 2 is a similar view of a portion of said apparatus showing a modified construction; Fig. 3 is a view taken on the line 1—1 of Fig. 2; Fig. 4 is a view showing partly in elevation and partly in section a portion of another modified construction of apparatus embodying my invention; Fig. 5 is a top plan view of a portion of the apparatus shown in Fig. 4; Fig. 6 is a view partly in side elevation and partly in vertical section of another modified construction of apparatus embodying my invention; and Fig. 7 is a top plan view of the apparatus shown in Fig. 6.

In Fig. 1 of the drawings, 10 designates a frame to which a pipe 11 is secured. In the construction as illustrated the pipe 11 is vertically arranged and communicates at one end with a gas conduit 12. The other end of said pipe is formed as a cock 13, the casing 14 of which is provided with hollow arms 15, two or more of which may be employed. These arms carry burners 28 and incandescent bodies, shown in the form of mantles, and designated in the drawings by the reference numerals 4 and 5. The reference

numeral 4 is employed to designate what I have termed the active incandescent body and the reference numeral 5 the inactive incandescent body which may be referred to 60 also as an additional or a reserve incandescent body. Any one of these incandescent bodies becomes active when the burner with which it may be associated becomes active or when any one of them may become associated with an active burner. The casing 14 is rotatable on the cock 13 and for the purpose of effecting rotating movement thereof it is provided with a toothed ring 16 which is engaged by a driving wheel 17 on a shaft 65 18 which is actuated by a coiled spring 19 in a casing 23, said spring being wound, for the purpose of storing up power, by means of a key 20. For controlling the movement of the shaft 18 a fan 21 is provided, the shaft 70 22 of which is connected with the shaft 18 in known manner by means of a gear wheel 22^a thereon and a gear wheel 22^b on said shaft 18. From the casing 14 arms 24 extend, the number of which corresponds to the 75 80 number of arms 15, and beneath the line or path of movement of the incandescent bodies a stop 25 is provided which is supported on an arm 26 which extends from the shaft 11. It will be understood that the stop 25 consists of material which is indestructible by 85 the action of the flame of the burner 28 thereon. A pin or projection 27 on each of the arms 24 is adapted to contact with the stop 25 as the casing 14 rotates under the influence of the power exerted by the coiled spring 19. The said pin or projection 27 consists of material which can be burnt, fused or weakened by the influence or action 90 of the heat of the flame of an active burner 95 situated in proximity thereto.

Normally the parts of the apparatus are in the position indicated in Fig. 1 in which one of the incandescent bodies, designated by the reference numeral 4, and its associated burner 28 occupy position immediately above the stop 25. The conduits for supplying gas are so arranged with respect to the passage-way through the cock 13 that gas for the flame is supplied to that burner which is 100 105 situated in proximity to the stop 25. The result is that the body designated 4 is acted upon by the flame and is thereby converted into a state of incandescence in which it is luminous. If the said body, which, in the 110 construction shown consists of a mantle, should rupture or break the flame of the

burner 28 would strike the pin 27 and render the same ineffective as a stopping element, it being understood that the said pin consists of material which would either burn, 5 fuse or become so weakened by the action of the flame of the burner thereon that it would cease to perform its function as a stop element and would permit the casing 14 together with the arms carried thereby to rotate under the influence of the power spring 19. When the element 27 is destroyed or rendered ineffective, as by burning or fusing, or is otherwise weakened, by the action of the flame of the burner 28, the ruptured, 10 burst or broken incandescent body 4 is moved forward as stated while the inactive additional or reserve incandescent body 5 and the stop element 27 in proximity thereto move forward into the position previously occupied by the incandescent body 4 and the stop element 27 in proximity thereto. The additional or reserve incandescent body 5 is stopped by the action of the stopping elements 15 and 27 in the same position as is at present 20 occupied by the active incandescent body 4. When it reaches that position gas is supplied from the conduit 12 to the associated burner, as is clearly shown in said Fig. 1 of the drawings. For bringing the additional or 25 reserve incandescent body 5 thus carried forward into the position occupied by the body 4 into operation or use its burner may be provided with a pilot flame which even in the inactive position of the incandescent body 30 is fed with gas from a special pilot flame conduit 29 which communicates with the gas supply conduit 11. Instead of such arrangement, however, the gas from the burner 28 which may be moved forward as 35 above described may be lighted by means of a pilot flame which is fed from a special conduit 30. Said conduit 30 may be provided as indicated in the construction shown in Fig. 1 in the arm 26 which carries the stop 25 and which may also carry a bearing 31 for the shaft 18 of the driving wheel 17. Although I have illustrated the arms 15 as being horizontally arranged it will be understood that they may be otherwise arranged 40 if desired without departing from my invention. It is also to be understood that the additional or reserve incandescent body or bodies may be moved forward as required and stopped in proper position and retained 45 as reserve or additional bodies in inactive position in any other manner and by any other means than that shown as may be desired.

In Figs. 2 and 3 of the drawings I have 50 shown a modified construction which comprises means whereby the pilot flame is automatically lighted and extinguished. In said Figs. 2 and 3, 14 designates, as in Fig. 1, the rotating cock casing, 15 the hollow arms 55 which carry the incandescent bodies, 4 the

active incandescent body, 24 the arms which are provided with the pins 27 to be burnt or fused or otherwise weakened, and 25 the stop for holding the arms 15 together with the incandescent bodies in stopped position with one of the said bodies, 4, over the stop 25. In the construction shown in the said Figs. 2 and 3 the stop 25 is arranged upon the end of a pivoted bar 32 which can be moved out of operative or stopping position, 60 say by being rotated on the stud 33, which projects from the supply pipe 11. 30 indicates the pilot flame conduit which communicates with a valve casing 34 (see Fig. 3, which shows a section of the valve casing on line 1-1 in Fig. 2), which is arranged on and carried by a hollow arm 31 which projects from the supply pipe 11, said arm 31 constituting the gas supply pipe for supplying gas to the pilot flame conduit 30, and 65 for this purpose communicates with the gas conduit 12 and with the valve casing 34. The bar 32 abuts against the spindle of the valve 35 and holds or keeps the valve closed owing to the action of the spring 19 on the stopped part 27 of the stopping arrangement whereas spring 37 tends to open the valve 35. 70

When the parts are in the position shown in Figs. 2 and 3 of the drawings in which position the incandescent body 4 is active and luminous, being rendered so by the flame of the burner 28, the bar 32 contacts with or abuts against the valve spindle 36 to hold the valve 35 in closed position so that the pilot flame is extinguished. If it should happen that the incandescent body 4 should become ruptured, burst or broken the flame of the burner 28 acts upon the stop device to release the parts which have been stationary, such release being effected, in the construction shown, by the fusing or the burning of or otherwise rendering ineffective the pin 27. Upon this occurrence the bar 32 is released and the spring 37 moves the same to the right, having reference to Fig. 3, the 75 valve 35 is opened and the flame of the burner 28 ignites the gas as it issues from the mouth of the conduit 30, the flame of which constitutes a pilot flame. Immediately, therefore, owing to the rotation of the cock casing 14, the flame of the burner 28 is extinguished, but when a succeeding incandescent body is moved forward into the position previously occupied by the incandescent body 4 the communication between the 80 burner 28 and the gas conduit 12 is restored through the cock 13 so that the pilot flame can ignite the gas which issues from the substituting burner. Simultaneously with the substitution of the reserve burner and the 85 reserve incandescent body associated therewith for the ruptured, burst or broken incandescent body and its associated burner a new or reserve pin 27 moves into contact with the stop 25 on the bar 32 and moves the 90

latter back to the position shown in Fig. 3 to close the valve 35 and thereby extinguish the pilot flame at the mouth of the conduit 30.

In Figs. 4 and 5 I have shown a modified construction of apparatus in which the gas from an additional or reserve burner is ignited before it reaches the place or position previously occupied by the burner associated with a previously ruptured, burst or broken incandescent body, with the result that the additional or reserve incandescent body which is associated with the said additional or reserve burner has already been heated and rendered luminous when it reaches the position previously occupied by the ruptured, burst or broken incandescent body. The frame, shown in Figs. 4 and 5, comprising the arms 15 carrying the additional or reserve incandescent body or bodies 5 is stopped and released in the same manner as in the construction shown in Figs. 2 and 3, that is, by the aid of the pins 27, the stop 25 and the arm 32, the latter being adapted to actuate the valve in the valve casing 34. From the valve casing 34 a pilot flame conduit extends, which, in the construction shown, is connected with the pipe 38 provided with a narrow outlet slot 39 or with a series of small out-flow holes. The pipe 38 extends from a point in proximity to and preferably beyond the position occupied by the active incandescent body 4 to a point in proximity to the position occupied by the next additional or reserve incandescent body 5. Said pipe 38 preferably is of arcuate shape, as shown in Fig. 5, and has a radius of curvature somewhat greater than the length of the arms 24 and 15 so as to position the same outside of the path of movement of their outer ends. It will be observed that the arm 15 is situated above the plane of the arcuate pipe 38 and also that the incandescent bodies 4-5, etc., which depend from the outer ends of arms 15 are situated slightly above the out-flow slot 39 of the arcuate pipe 38, as best shown perhaps in Fig. 4 of the drawings. When the active incandescent body 4 or any one of the additional or reserve incandescent bodies which may have been moved into the position occupied by the said active body 4, ruptures, bursts or breaks so that the flame of the active burner acts upon the element 27 of the stopping means to burn, fuse or otherwise weaken the same or render it ineffective so as to permit movement of the frame, comprising the arms 15, the valve in the valve casing 34 is released as described in connection with Figs. 2 and 3 and a flame is lighted in the slot 39. This flame ignites the shellac coating upon the incandescent body 5 consisting, in the construction shown, of a mantle, it being understood that these incandescent bodies are usually coated with a

shellac or equivalent coating. During the forward movement of the additional or reserve body 5 its burner is brought into communication with the gas supply pipe 11 by means of suitable holes or passageways in the cock casing 14 whereby a flame may be lighted in the said burner. Said flame may constitute a pilot flame for the main flame, lighted when the incandescent body 5 reaches the position previously occupied by the ruptured, burst or broken incandescent body 4, or it may constitute a main flame whereby the incandescent body reaches the said position in fully active and luminous condition.

The arrangement in Figs. 4 and 5 just described is especially adapted for burning the shellac cover or coating of the mantle before the gas is admitted to the burner.

In Figs. 6 and 7 I have shown a modified construction of apparatus embodying my invention in which a movable frame carrying a plurality of incandescent bodies is provided and in which a single burner is provided for co-operating successively with the said bodies. In the said Figs. 6 and 7, as in the preceding figures, 11 designates a supply pipe or conduit through which gas is adapted to be supplied through a passage-way in an arm 40 to a burner 41. In the construction shown the arm 40 is detachably connected with the supply pipe or conduit 11 but it may be otherwise rigidly and stationarily secured thereto. In the construction shown in these figures the incandescent body which is shown in proximity to the burner 41 is designated by the reference numeral 4 while the others of said bodies are designated by the numeral 5. These bodies are carried upon the outer ends of arms 42 which radiate from a central hub 43 which is revolvably mounted upon the reduced upper end portion 44 of the pipe or conduit 11. The said hub is held in position by means of the ring 45 which is secured to the reduced end portion 44 by means of a binding screw 46. Although there are four arms 42 in the construction as illustrated it will be understood that a greater or less number of arms may be employed as may be desired. The hub 43 is provided with a gear 47 which is engaged by a pinion 48 upon the upper end of a driving shaft 18 which is driven by the mechanism as illustrated in Fig. 1 of the drawings. The upper end portion of the shaft 18 extends through an opening in a laterally extending arm 26 which is secured by means of a sleeve 50 to the pipe or conduit 11 being held in place thereon by means of a binding screw 51. The outer end portion of the arm 26 is provided with a passageway 52 having connection through a pipe 53 with the gas passageway in the pipe or conduit 11. Through the pipe 53 and the passageway 52 gas is supplied to a pilot burner 54 which is located in proximity to the incandescent

body 4 which is situated underneath and in coöperative relation with the burner 41. The purpose of the pilot burner 54 is to ignite the gas from the burner 41 in case the 5 flame of the latter should be extinguished by the movement of an arm 42 and an incandescent body into position underneath the same. Should it occur that the flame of the burner 41 should be thus extinguished it is 10 desirable and necessary that means such as the pilot burner 54 be provided for re-igniting the same. The incandescent bodies 4 and 5 (which in the constructions shown are 15 in the form of mantles) are supported underneath flattened portions 55 at the outer ends of the arms 42. These flattened portions are provided with holes 56 through which the flame from the burner 41 acts upon the said incandescent bodies when they 20 occupy the position with respect thereto indicated by the body 4 in Figs. 6 and 7. As in the previous figures, 25 designates an indestructible stop member which is adapted to coöperate with the stop member 27 which 25 is adapted to be rendered ineffective by burning or otherwise when the incandescent body 4 is ruptured so as to permit the flame from the burner 41 to act thereon. The stop members 27 are carried upon the lower ends 30 of arms 60 which depend downwardly from the radial arms 42.

In the form of construction illustrated in Figs. 6 and 7 a single burner is employed which is adapted to coöperate successively 35 with the incandescent members which are carried upon the outer ends of the arms 42. When the incandescent member which is in position underneath the burner 41 is ruptured whereby the stopping means is rendered ineffective the action of the spring 19 through the pinion 48 causes rotation of the gear 47 and the arms 42 having connection therewith so as to move the next succeeding arm 42 with the incandescent body thereon 45 into the position underneath the burner 41.

I claim:—

1. In an apparatus for automatically exchanging incandescent bodies, the combination of burners, an incandescent body associated with an active burner, an additional incandescent body associated with an inactive burner, means tending to move the said burners and the said bodies so as to move the inactive burner and its associated body into 55 the position occupied by the active burner and its associated body whereby said inactive burner is brought into activity, and stopping means for retaining the said burners and bodies in predetermined positions 60 said stopping means including a part adapted to be rendered ineffective by the action thereon of the flame of the active burner in case its associated incandescent body should become ruptured to permit the passage of the 65 flame to the stopping means.

2. An apparatus for automatically exchanging incandescent bodies comprising burners and an incandescent body associated with each burner, one burner and one body being active and the remaining burner or 70 burners and body or bodies being inactive, a stopping device for retaining the said active burner and body in active position and the remaining inactive burner or burners and body or bodies in inactive position, said stopping device including a member adapted to be rendered ineffective by the action of the flame of the active burner should the incandescent body associated therewith be ruptured, and means for automatically moving 75 a reserve burner and its associated reserve body into active position when said active body is ruptured.

3. An apparatus for automatically exchanging incandescent bodies comprising 85 burners and an incandescent body associated with each burner, one of said burners being active and the other or others inactive, a movable frame supporting such burners and incandescent bodies, means tending to move 90 said frame, and stopping means for holding said frame in certain predetermined positions said stopping means comprising members adapted to contact with each other, one of which members is adapted to be rendered ineffective by the action of the flame of the active burner thereon when said incandescent body is ruptured.

4. An apparatus for automatically exchanging incandescent bodies, said apparatus comprising a plurality of burners and incandescent bodies associated respectively therewith, means for causing movement of the said burners and the bodies associated therewith, and means for retaining the said burners in predetermined positions in which one of the said burners is active while the other or others are inactive, such means including a part adapted to be rendered ineffective by the action of the flame of the active burner in case the incandescent body associated therewith should become ruptured.

5. In an apparatus for automatically exchanging incandescent bodies, a movable cock casing carrying an incandescent body, a power device for actuating said casing, a cock in said casing communicating with a gas conduit, a burner for said incandescent body, and stopping means for resisting said power device and holding the said casing against actuation, said stopping device being rendered ineffective by the action of the flame of the burner thereon upon the rupturing of the said incandescent body.

6. In an apparatus for automatically exchanging incandescent bodies, the combination of a movable cock casing, means tending to move said casing, a cock in said casing communicating with a gas conduit, a burner terminating said gas conduit, an incandes-

- cent body associated with said burner, a pilot flame conduit, means for closing the said pilot flame conduit, stopping means for retaining the said movable cock casing in predetermined position, said stopping means being adapted to operate upon said means for closing the said pilot flame conduit to close the same, the said stopping means including a member which is adapted to be rendered ineffective by the action of the flame of the said burner thereon when the said incandescent body is ruptured, burst or broken.
7. In an apparatus for automatically exchanging incandescent bodies, the combination of a movable cock casing, means tending to cause movement of said casing, a cock in said casing communicating with a gas conduit, a burner for said incandescent body terminating said conduit, an incandescent body associated with said burner, a pilot flame conduit, means for closing said pilot flame conduit, and stopping means for retaining the said movable cock in predetermined position, the said stopping means including a member adapted to act upon the means for closing the said pilot flame conduit and the said stopping means also including a member which is adapted to become ineffective upon the action of the flame of the burner thereon when said incandescent body is ruptured, burst or broken to thereby release the said movable cock to permit movement thereof.
8. In an apparatus of the character described, the combination of a movable member, a power device for causing movement of the said member, incandescent bodies and burners associated respectively with said bodies carried by said movable member, means for retaining the said member in predetermined positions, means for supplying gas to that burner which is situated in proximity to the means for retaining the said member in stopped position, said retaining means including a member which is adapted to be rendered ineffective by the action thereon of the flame of the burner in proximity thereto when the incandescent body associated with such burner is ruptured to thereby release the said movable member and permit further movement thereof into a succeeding predetermined position.
9. In an apparatus of the character described, the combination of a rotatable member having arms extending laterally therefrom said arms being provided with burners, bodies carried upon said arms and associated respectively with said burners which bodies are adapted to become incandescent by the action of heat thereon, means for causing rotation of said rotatable member, means for holding the said rotatable member against rotation, said means being situated in proximity to one of said bodies when the said rotatable member is in stopped position, a member carried by said rotatable member for coöperating with the said retaining means, and means for supplying gas to the said burner situated in proximity to the said retaining means when the said rotatable member is held against rotation, the said member for coöperating with the said retaining means being adapted to be rendered ineffective by the action of the heat of the flame of the burner thereon.
10. In an apparatus of the character described, the combination of a movable member provided with a plurality of incandescent bodies, one of which is active and the others of which are inactive, means for supplying gas for a flame which heats the active incandescent member, and means for causing movement of the said movable member, stopping means for retaining the said movable member and said bodies in stopped position, said stopping means being adapted to be rendered ineffective by the action of said flame thereon when the said active body is ruptured to thereby release said member and permit movement thereof to carry a succeeding or additional incandescent body into the position previously occupied by the active incandescent member.
11. In an apparatus of the character described, the combination of a stationary tubular member one end of which communicates with a gas supply conduit and the other end of which terminates in a cock, a member rotatably supported upon said cock, said member being provided with arms terminating in burners and the said arms supporting at their ends incandescent bodies, and the said arms being provided with passage-ways extending longitudinally thereof, means for causing rotation of the said rotatable member to bring the passageways in the said arms successively into alignment with a hole in the said cock which communicates with the said tubular member, means for holding the said rotatable member in stationary position, said means comprising a movable and a stationary member the latter being situated in proximity to an incandescent body when the said rotatable member is in stopped position, the said movable member consisting of material which is adapted to be rendered ineffective by the action of the flame of the burner acting thereon, and means for igniting the burner which is situated adjacent to the said stationary stopping member.
12. In an apparatus of the character described, the combination of a rotatable member carrying a plurality of bodies adapted to be rendered incandescent by the action thereon of a flame, means for causing rotation of said member, means for holding the said member against rotation, said means including a part which is adapted to be rendered ineffective by the action of heat thereon, means for supplying gas for the flame

for rendering incandescent the incandescent member situated in proximity to the said stopping means, and means for igniting the said gas.

5 13. In an apparatus of the character described, the combination of a rotatable member having a plurality of arms provided with passage-ways therethrough for the passage of a gas, means for causing rotation of the said member; and a conduit for supplying gas to the passage-ways in said arms as the latter are brought successively into a predetermined position.

10 14. In an apparatus of the character described, the combination of a rotatable member provided with a plurality of passage-ways for the passage of a gas therethrough said passage-ways terminating in burners, incandescent members associated with the said burners, means for causing rotation of the said rotatable member, means for supplying gas to the passage-ways in said rotatable member as such passage-ways are brought successively into a predetermined 20 position, means for igniting the gas in the burner of such passage-way when the gas escapes therefrom, and stopping means for controlling the rotary movement of said member, the said stopping means being adapted to be rendered ineffective by the action 25 of the burner flame thereon.

15 15. In an apparatus of the character described, the combination of a movable member carrying a series of bodies adapted to become incandescent by the action of heat thereon, one of the said bodies being active and the other or others of said bodies being inactive, and means acting automatically upon the rupturing of an active body to move an inactive body into the position 30 previously occupied by said ruptured body.

20 16. In an apparatus of the character described, the combination of a plurality of burners and a body adapted to become incandescent upon the application of heat thereto associated with each burner, and means acting automatically upon the rupturing of an active body for causing movement of said ruptured body and an associated 25 burner and for causing simultaneous movement of a formerly inactive body and its associated burner into the position previously occupied by said ruptured body and its associated burner.

30 17. In an apparatus of the character described, the combination of a rotatable member having a plurality of arms extending therefrom, said arms being angularly arranged with respect to each other and each 35 of them terminating in a burner, means for causing rotation of said member, stopping means for retaining said member in stopped position with a burner in proximity to said stopping means, means for supplying gas to said burner, a pilot burner of arcuate shape

and extending from a point in proximity to said burner a distance toward the next succeeding burner, and means for supplying gas to said pilot burner.

18. The combination of an incandescent body rendered active by the action of a flame thereon and a reserve incandescent body and automatic means rendered operative by the action of said flame upon the rupturing of the active body for causing the 75 reserve body to take its place.

19. The combination of an incandescent body, means for supplying a flame to render said incandescent body luminous, a reserve incandescent body, and means rendered operative upon the rupturing of the first-named incandescent body for causing the reserve incandescent body to take its place.

20. The combination of an incandescent body, means for rendering said body luminous, a reserve incandescent body and means rendered operative upon the rupturing of the first-named incandescent body whereby said reserve incandescent body is caused to 90 become luminous.

21. The combination of an incandescent body, means for supplying a flame to render the said body luminous, a reserve incandescent body, and automatic means rendered operative by the heat of said flame upon the rupturing of the first-named body for causing the reserve body to move into the position previously occupied by the said first-named body where it is subjected to said 100 flame and thereby rendered luminous.

22. The combination of a pilot flame burner, a plurality of incandescent bodies, supporting means for said incandescent bodies, means for arresting the said bodies 105 with one of them in coöperative relation with respect to the said pilot flame burner, means for supplying a flame for rendering the last mentioned body luminous, and automatic means rendered operative upon the rupturing of said luminous body for moving said ruptured body away from the pilot flame burner and for causing another body to take its place.

23. The combination of a pilot flame 115 burner, a plurality of movable arms each carrying an incandescent body, means for retaining the said arms in position with the body carried by one of them in coöperative relation with respect to the pilot flame 120 burner, means for applying heat to the last mentioned body to render the same luminous, and automatic means rendered operative upon rupture of the said luminous body for moving the arms to carry the said 125 ruptured body away from the pilot flame burner and for causing another body carried by one of the arms to take its place.

24. In an apparatus of the character described, the combination of a plurality of 130

movable members each supporting an incandescent body, means for supporting the said members, means for causing movement of the said members, means for supplying a flame to render one of said incandescent bodies at least luminous, stopping means for arresting the said members in predetermined position, one member of the said stopping means being situated stationarily in proximity to the position at which a body is adapted to be rendered luminous by such flame, and other elements of the said stopping means having connection respectively

with the said movable member and being movable in unison therewith, the said stopping means being rendered ineffective by the action of said flame when the said luminous incandescent body is ruptured to thereby release the said movable members and permit movement thereof.

15

In testimony whereof I have affixed my signature in presence of two witnesses.
